RURAL LINE REPEATER

Carl Oman Wright, Chicago, and Edward Sigford Peterson, Elmwood Park, Ill., assignors to Associated Electric Laboratories, Inc., Chicago, Ill., a corporation of Delaware

Application March 16, 1938, Serial No. 196,114

19 Claims. (Cl. 179—17)

The present invention relates to improvements in telephone systems and has for one of its objects the provision of improved apparatus for terminating rural subscribers' lines of the multiparty type in a telephone exchange which utilizes automatic switching equipment for setting up connections between the various lines of the system.

In the usual arrangement of existing installed automatic exchanges wherein certain of the lines extending to the exchange are of the rural multiparty type and others are of the single party type, no differentiation is made between the lines as regards the mode of terminating the lines in the automatic switching equipment. As a result, the initiation of reverting calls on the rural lines invariably results in the seizure of certain of the automatic switching equipment provided in the terminating exchange. More particularly, when a reverting call is initiated on a rural line, one of the non-numerical automatic switches provided in the exchange is assigned to the use of the line having the calling condition created thereon and operates to switch the calling line through to one of the numerical switches. In certain instances the seized switches are held operated throughout the duration of the reverting call. In other systems, apparatus is provided for causing the release of the operated switches after a predetermined time interval has elapsed following the seizure of the switches. In either case, certain of the automatic switching equipment is tied up so that it cannot be used by the other lines.

It is a further object of the present invention, therefore, to provide in an automatic telephone system improved apparatus of exceedingly simple arrangement for preventing any of the regular switching equipment from being taken for use by a line having access to the equipment when a reverting call is initiated on the line.

It is a further object of the invention to provide improved apparatus of extreme simplicity for guarding the rural lines against seizure by the automatic equipment when the lines are engaged with calls of the reverting type.

In the illustrated embodiment of the invention, the several multiparty rural lines of the system extend to an automatic exchange and are arranged to have access to certain of the non-numerical automatic switches provided in the exchange and to be accessible to certain of the numerical switches also provided in the exchange. More particularly, each rural line terminates in a repeater, and each repeater is connected by way of a trunk line to the automatic switching

equipment. Each rural line has associated therewith a plurality of local battery substations and each of the substations conventionally comprises a telephone, an impulsing device, a hook switch for connecting the telephone across the conductors of the associated line, and an alternating current magneto generator adapted for use in signaling between the substations of the associated line on reverting calls. In accordance with one feature of the present invention there is provided in each repeater a relay operative in response to the operation of any one of the generators provided in association with the associated line for preventing the line from taking any one of the non-numerical switches for use and for marking the associated line as busy, thereby to prevent the line from being seized by any one of the non-numerical switches. Also included in each repeater is a pulsing relay which is operative to complete a loop circuit to one of the non-numerical switches when a regular call is initiated on the associated line and is arranged to respond to impulses dialed at the calling substation and to repeat the impulses to the automatic switching equipment. For the purpose of marking the respective rural lines as busy, when reverting calls are initiated at the substations associated therewith, there is provided a timing device which is operative through a predetermined cycle each time its operation is initiated and is arranged to hold operated for a predetermined time interval any operated ones of the relays respectively associated with the rural lines which function individually to mark the respective lines as busy. This timing device comprises a switch having a home position and operative to a predetermined off-normal position, an output terminal, a start relay, apparatus responsive to the operation of the start relay for initiating the operation of the switch, and apparatus controlled by the start relay and the switch for applying and maintaining a predetermined potential on the output terminal for a predetermined time interval. The start relay is connected and arranged to respond to the operation of any one of a plurality of alternating current relays individually associated with the respective rural lines and the arrangement is such that the switch incorporated in the timing device is returned to its home position to start a new cycle of operation of the timing device each time one of the alternating current relays is caused to operate.

A further feature of the invention relates to the provision of a test connector switch by way of which a connection may be routed to any of the

rural subscribers' lines for the purpose of determining the condition of these lines. Each of the lines is normally connected to be accessible to the regular connector switches, but there is provided in association with each line a line switching relay arranged to be controlled by the test connector switch and operative to rearrange the circuit connections so that the associated line is accessible to the test connector switch. In order to prevent this test connector switch from seizing the lines at times when they are busy, certain of the control relays embodied in the respective repeaters and operative when the associated lines are made busy in connections not routed by way of the test connector switch, are arranged to render the test connector switch ineffective to control the particular line switching relay associated therewith.

Further features of the invention pertain to the particular arrangement of the circuit elements whereby the above-outlined operating features are obtained.

The novel features believed to be characteristic of the invention are set forth with particularity in the appended claims. The invention, both as to its organization and method of operation, together with further objects and advantages thereof, will best be understood by reference to the specification taken in connection with the accompanying drawing. In the drawing, Figures 1 and 2 illustrate an automatic telephone system having incorporated therein the features of the present invention as briefly outlined above.

Referring now to the drawing, the system there illustrated comprises, in general, an exchange, a plurality of single party subscribers' lines, two of which are indicated at 172 and 173 extending to the exchange, and a plurality of subscriber-controlled automatic switches including the two line switches 10 and 50, respectively, a selector switch 20, and two connector switches 30 and 40 respectively, for setting up connections between the various subscribers' lines. It is pointed out that the line switches 10 and 50 and the other similar switches corresponding thereto are non-numerical switches in the sense that they are ineffective to perform any line selecting functions other than those of selecting idle ones of the selector switches. The selector and connector switches, on the other hand, are commonly known as numerical switches in that they are operative to perform particular line selecting functions in response to impulses transmitted thereto. It will be understood that a plurality of switches of each type, namely, a plurality of line switches, a plurality of selector switches, and a plurality of connector switches, are provided in the system for performing the usual line switching functions. The switches of each type are respectively arranged in groups and, in accordance with universally followed practice, the number of switches in each group is determined by the maximum volume of traffic the particular switch group is required to handle. Further in accordance with conventional practice, each of the automatic subscribers' lines is multiplied between the corresponding bank contacts of a group of connector switches, whereby a plurality of such switches are available for setting up connections between each line and every other line of the system. The line switches, on the other hand, are individually associated with the respective subscribers' lines, that terminating the line 172 being indicated at 10.

The end of each automatic subscriber's line remote from the exchange terminates in a subscriber's substation which may be of any desired arrangement. Two such substations are diagrammatically illustrated at B and C in association with the lines 172 and 173, respectively. In brief, each of the substations may comprise the usual hand set type of transmitter and receiver, a hook switch, a ringer, and an impusing device for transmitting the switch control impulses by way of the associated line to the automatic switching equipment located in the terminating exchange.

Each of the line switches 10, 50, etc., is preferably of the well-known rotary type, of which there are several commercial embodiments. Each of the selector and connector switches is preferably of the well-known Strowger type having embodied therein a wiper carriage structure adapted to be translated vertically to bring the wipers thereof to a position opposite a particular level of bank contacts and then rotated to bring the wipers into engagement with a particular set of contacts in a selected level; vertical, rotary and release magnets; and control relays suitably connected and arranged to control the energization of the various magnets and the line switching in accordance with the particular functions of the switch. Obviously, the particular arrangement of the control apparatus embodied in the switches of different type is different in each instance depending upon the character of the switch.

Also extending to the exchange housing the automatic switching equipment briefly described above are a group of rural subscribers' lines, one of which is indicated at 86. Each of these lines is of the multiparty type having associated therewith a plurality of subscribers' substations. One such substation is illustrated in detail and indicated generally at A in association with the line 86, and a second substation associated with the same line is indicated diagrammatically at D. Each of these rural lines terminates in a repeater, and each repeater is connected by way of a trunk line to have access to and to be accessible to the automatic switching equipment provided in the exchange. Thus, the line 86 terminates at a repeater 160 which is connected by way of a two-way trunk line 155 to the non-numerical line switch 50 and the numerical connector switch 40. For the purpose of marking the various rural lines as busy when these lines are respectively engaged in reverting call connections, there is provided a timing device indicated generally at 200 which is commonly associated with all of the rural subscribers' lines. This device cooperates with certain of the control relays provided in the respective repeaters to busy the repeater trunk lines when the respective associated subscribers' lines are occupied with reverting calls.

Code ringing is utilized for selectively signaling the various substations associated with each of the rural subscribers' lines. To this end, suitable provisions are made in the connector switch 40 and the other corresponding switches for selecting the proper coded ringing current to signal a desired substation on a selected line.

Neglecting for the present the details of the apparatus provided in association with the rural subscribers' lines, the system as described above is, in general, entirely conventional in form and its operation is well understood in the art. In brief, when a subscriber, such, for example, as the subscriber at the telephone B, initiates a call over the line 172 to a second subscriber's tele-

phone, such, for example, as the telephone C, by lifting his receiver from its hook, a loop circuit is completed for initiating the operation of the line switch 10 to select a trunk line leading to an idle selector switch. Assuming, for example, that the selector switch 20 is the first numerical switch selected by the line switch 10 for the use of the calling line 172, when the trunk line lead-link to this selector switch is found, the loop circuit is extended to this selector switch and the switch is conditioned to respond to the first series of impulses dialed at the calling substation. With the selector switch 20 in this condition, dial tone is returned over the established loop to the calling subscriber to indicate that the dialing operation may be started. When the first digit is dialed at the calling substation, the switch 20 elevates its wipers to a position opposite the level of bank contacts terminating the trunks leading to the connector switches having access to the called line 173. Following this operation, the wipers of the switch 20 are automatically stepped over the contacts of the selected level until a trunk leading to an idle connector switch of the selected group is found. Assuming that the connector switch 30 is the first idle connector switch available in the selected group, when the wipers of the switch 20 are stepped into engagement with the contacts terminating the trunk extending to this connector switch, the subscriber's loop circuit is extended thereto, thereby to cause this connector switch to be conditioned to respond to the second and third series of impulses dialed at the calling substation. In response to the dialing of the second digit, the wipers of the connector switch 30 are stepped vertically to a position opposite the level of bank contacts at which are terminated the lines of the ten-line group including the called line 173. Following this series of impulses, the connector switch is conditioned to rotate its wipers step by step in accordance with the impulses making up the third and final digit dialed at the calling substation. When the last digit is dialed, the wipers of the switch 30 are stepped into engagement with the set of bank contacts terminating the called line 173. In accordance with conventional practice, suitable provisions are made for testing the called line to determine its idle or busy condition, for returning busy tone over the established loop to the calling subscriber in case the called line is busy, and for applying ringing current to the called line in the event this line is idle at the time it is selected. Assuming that the called line is idle, the desired conversational connection is completed when the called substation is answered. Also in accordance with conventional practice, the apparatus is arranged to insure its release when the connection is cleared out at the calling and called substations. Any desired mode of initiating the release of the established switch train may be utilized. For example, the control apparatus embodied in the connector switch 30 may be arranged so that the release of the connection is entirely under the control of the calling part. Alternatively, the apparatus may be so arranged that the release of the connection is under the control of the last party to hang up.

Referring now more particularly to the apparatus provided in association with the several rural lines, it is pointed out that the arrangement of the substation equipment may be identical for all of the substations. For this reason, only the apparatus located at the substation A has been illustrated in detail. In brief, this ap-

paratus comprises a transmitter 73, a receiver 74, and means comprising a hook switch 80 for connecting the two elements noted to the associated line. This substation is of the local battery type, a battery 75 being provided as a vehicle for generating voice frequency voltages when sound waves impinge upon the diaphragm of the transmitter 73. Such voltages are impressed between the conductors C87 and C88 of the line 86 by a transformer 70. There is also provided at the substation A a signal device 76 in the form of a polarized ringer, a manually operable alternating current generator 78, and a dial actuated impulsing device 77.

The repeater 160 at which the line 86 terminates is identical in all respects with the other repeaters respectively associated with the other rural subscribers' lines. In brief, this repeater comprises the usual transformer as indicated in the drawing and an alternating current relay 20 R120 connected and arranged to operate only in response to the operation of any one of the magneto generators respectively located at the substations associated with the line 86. This repeater further comprises a ringing relay R110 25 which is operative in response to the seizure of the trunk line 155 to cause coded ringing current to be projected over the line 86; a relay R130 for busying the subscriber's line 86 thereby to prevent this line from being seized by any one 30 of the numerical connector switches when the line is engaged in a reverting call connection; a pulsing relay R150 which is connected and arranged to respond to any one of the impulsing devices provided at the substations associated 35 with the line 86; and a slow-acting relay R140 which functions to control the relay R130. The relay R130 further functions to open a point in the loop circuit extending to the line switch 50, thereby to prevent this line switch from operating to seize one of the selector switches when the line 86 is occupied with a reverting call.

Since the relay R130 is arranged to be energized only while one of the magneto generators is being operated, it is evident that suitable provision should be made for holding this relay operated continuously during the interval required for a complete reverting call ringing operation and for the further interval which elapses between the end of the ringing operation and the 50 instant when the calling telephone is connected to the line. It is for this purpose that the timing device 280 is provided. In brief, this timing device comprises a rotary switch 250 having a home position and operative to a predetermined 55 off-normal position, an output terminal 215, means comprising a start relay R210 for initiating the operation of the switch 250 and for applying a predetermined potential, namely, ground potential, to the terminal 215, and means 60 comprising the switch 250 and the relays R220, R230 and R240 for maintaining ground potential on the output terminal 215 for a predetermined time interval. The rotary switch 250 is of the well-known minor type and comprises a single set of bank contacts 251, a wiper 252 associated with the contact set 251, means comprising an operating magnet 253 and a ratchet and pawl mechanism, not shown, for driving the wiper 252 over the contacts of the set 251, off-normal 70 springs 255, and means comprising a release magnet 254 for causing the switch to be returned to its normal or home position. The arrangement is such that the switch 250 is returned to its home position and starts a new operating 75

cycle each time the start relay R110 is energized. This relay is connected to be energized in response to the operation of any one of the alternating current relays corresponding to and including the relay R120. Hence, it will be apparent that a new operating cycle of the timing device is initiated each time one of the alternating current relays is caused to operate.

As indicated above, suitable provisions are made for routing test connections from an exchange attendant's telephone to the various rural subscribers' lines to determine whether or not the lines are faulty. Such connections are routed by way of the test connector switch 60 to any desired one of the rural lines. Since the selection of the desired one of these lines may occur when the desired line is busy, it is necessary to arrange the apparatus so that the test connector switch cannot gain access to busy lines. To this end, the relay R100 is provided, which relay is normally deenergized but is arranged to operate, only if the line 86 is idle, in response to the operation of the test connector switch 60, to the particular position corresponding to this line. This relay upon operating functions to busy the line, thereby to prevent its seizure by any other of the connector switches and, further, to disconnect the line from the repeater 160.

The operation of the automatic switching apparatus to extend a connection to one of the multiparty rural subscribers' lines from one of the other subscribers' lines is, in general, quite similar to the operation of the apparatus to set up a connection between the lines 172 and 173 in the manner pointed out above. More particularly, if a call to the substation A is initiated at the substation B, the automatic switch 10 and the switches 20 and 40, or other similar switches, may be caused sequentially to operate to select the called line 86 in response to the dialing of the required three digits. Assuming the line 86 to be idle, when the line selecting operation is completed, ground is applied to C156 by the connector switch 40, thereby to mark the line 86 as busy and to cause the partial operation of the line switch 50 to clear the trunk line 155 of impedances which might interfere with the transmission of ringing and voice frequency currents. As indicated above, each of the connector switches having access to the line 86 and the other rural lines has associated therewith ringing apparatus for applying coded ringing current to the called or selected line. Hence, the calling party, upon dialing the final or code selecting digit or digits, conditions the selected connector switch 40 to apply to the called line 86 coded ringing voltage of the character identifying the called substation A. When the ringing operation is started, the high potential terminal of the ringing generator is connected to C153 by the ringing relay during each ringing interval and the grounded terminal of the ringing current source is connected to C157. The application of ground to C157 results in the completion of a circuit for energizing R110, this circuit extending from ground on C157 by way of RA151, RC152 and the winding of R110 to battery. The relay R110 operates at the beginning of each ringing interval to connect, at RA114 and RC115, the line conductor C88 to the trunk line conductor C158 and to connect, at RA112, the opposite line conductor C87 to the grounded contact RC111, thereby to provide an uninterrupted path for the ringing current. This path

extends by way of the conductors of the line 86 and through the various ringing devices connected across the line 86, in parallel. Obviously, at the end of each ringing interval, ground is removed from C157, causing R110 to restore. Thus, R110 is repeatedly energized to cause the coded ringing current to be transmitted out over the called line. Since in the present assumed case the projected current is coded in accordance with the signal corresponding to or identifying the substation A, the signal device 76 in its response to this current indicates that the substation A is being called.

The call is answered in the usual manner by removing the receiver 74 from the hook which forms the actuating element for the hook switch 80, causing the springs of this switch to be moved to their respective off-normal positions. When the springs 81 are moved into engagement, the receiver 74 is connected across the conductors C81 and C88 of the line 86 over a path including the secondary winding 72 of the repeating coil 70. When the springs 83 are closed, the transmitter 73 is connected in a closed circuit comprising the primary winding 71 of the repeating coil 70 and the local battery 75. Thus, the receiver 74 is connected to respond to voice frequency currents transmitted from the substation B, and the transmitter 73 is connected to generate voice frequency currents in response to sound waves impinging on the diaphragm thereof. When the springs 82 are moved into engagement, a simplex circuit is completed for energizing the line relay R150, this circuit extending from ground at the lower spring of the set 82 by way of the impulsing springs embodied in the impulsing device 77, the lower winding of the ringer 76, C88, RA105, RA114, RC116, the lower winding of R120 and through the winding of R150 to battery. A parallel branch of this simplex circuit extends by way of the upper winding of the ringer 76, C87, RA104, RA112, RC113, the upper winding of R120 and through the winding of R150 to battery. Although both of the windings of R120 are energized when the above described circuit is completed the fluxes produced thereby are in opposition and, hence, this relay does not operate. The relay R150, however, operates to complete, at RA151 and RC153, a loop circuit extending back to the operated connector switch 40. The completion of this loop circuit causes the operation of the ring cut-off relay provided in the connector switch 40, in the usual manner. When the ring cut-off relay operates, the talking connection between the calling and called substations B and A, respectively, is fully completed. The apparatus remains in this condition until the connection is cleared out.

When a connection is once established in the manner described in the immediately preceding paragraphs, it is fully released only when the calling and called parties restore the respective hook switches provided at the substations A and B to normal. Thus, when the calling party at the substation B hangs up, the connector switch 40, the selector switch 20, and the line switch 10 are sequentially restored, in the order named, and in the manner pointed out above. The repeater is released when the called party at the substation A restores the receiver 74 to its hook to interrupt, at the springs 82, the above-traced operating circuit for R150, this relay being the only operated relay in the repeater. When the switch 80 is returned to normal, the springs 81 are opened to disconnect the receiver 74 from

across the conductors of the line 86, and the springs 83 are opened to interrupt the above-traced circuit including the transmitter 73.

Since the line 86 and the other similar rural lines are of the party line variety, it is incumbent upon anyone initiating a call to first ascertain whether or not the line associated with the calling substation is busy. Assume, for example, that a person at the substation A desires a connection to the substation C. Before initiating the call, the calling party should first operate the switch hook latch 85 to its off-normal position and then remove the receiver 74 from its hook to listen in on the line 86. It will be noted that, when the latch 85 is moved to the off-normal position, the springs 81 are closed to connect the receiver 74 across the conductors of the line 86. Moreover, with this latch occupying the off-normal position, the movable springs of the switch 80 are restrained in normal position so that the springs 82 and 83 remain open-circuited. If the line is idle, the calling party may move the latch 85 to its normal position to close the springs 82 and 83. When this is done, the above-traced circuit including the transmitter 73 is completed, the receiver 74 is connected across the conductors of the line 86, and the simplex circuit, traced above, is completed for energizing the line relay R150. The relay R150 now operates to complete, at RA151 and RC153, the above-mentioned loop circuit for initiating the operation of the line switch 50 to select an idle selector switch. Specifically, this loop circuit extends from the trunk line conductor C157 by way of RA151, RC153, RA132, the repeater winding 163, the resistor 165, the repeater winding 164 and RA135 to the opposite trunk line conductor C158. Assuming, for example, that the line switch 50 selects the selector switch 20, and the selector switch 20, in turn, operates in response to the dialing of the first digit at the substation A to select the connector switch 30, the operation of each of the two last-named switches to perform its line selecting and auxiliary functions is identical with that set forth above. In this connection it is noted that, each time the springs of the impulsing device 71 are opened during the dialing operation, the operating circuit for R150 is interrupted causing this relay to restore to open the loop circuit as extended to either the selector switch 20 or the connector switch 30. Thus, impulses are transmitted to each of these two switches to cause the line selecting operations to be performed. Obviously, when the dialing operation is completed, R150 is held energized and, in turn, maintains the loop circuit extending to the line switch 50 closed. Immediately the line switch 50 operates to extend the loop circuit to a selected selector switch ground is applied to C156, thereby to mark the line 86 as busy and to prevent its seizure by another of the connector switches.

The connection as established to the substation C in the manner just described is only completely released when the hook switch 80 is returned to its normal position. Restoration of the switch 80 to normal causes the operating circuit for R150 to be interrupted at the switch springs 82. Ground potential is removed from the control conductor C156 when the operated switch train is released. Thus, the repeater 160 is conditioned for further use and the line 86 is marked as being idle.

As pointed out in the introductory portion of the specification, the arrangement of the apparatus is such that none of the regular switching

equipment provided in the automatic exchange is taken for use when a reverting call is initiated at one of the substations connected to one of the rural lines. If, for example, a call to the substation D is initiated at the substation A, the calling party first actuates the hook latch 85 to its off-normal position to connect the receiver 74 between the conductors of the line 86 in the manner pointed out above. The calling party now listens in to determine whether the line 86 is busy or idle. If the line is found to be idle, the calling party may initiate the call by actuating the hand magneto 78 to project ringing current over the conductors of the line 86. Before performing the ringing operation, however, the calling party should restore the receiver 74 to its hook and actuate the latch 85 to its normal position. By turning the hand crank of the magneto 78 to generate ringing current coded in accordance with the call signal designating the substation D, the signal device at this substation may be caused audibly to indicate that the substation is being called. Each time the magneto 78 is operated, current is supplied to the alternating current relay R120 to cause its operation. The path of this current extends from one terminal of the generator 78 by way of the springs 89, the line conductor C87, RA104, RA112, RC113, the two windings of R120 in series, RC116, RA114, RA105, and C88 to the opposite terminal of the generator 78. In response to its energization over the above-traced circuit, R120 operates to complete, at RA121, a circuit for energizing R130 and, at RA122, a circuit extending by way of the start conductor C170 for energizing the start relay R210 provided in the timing device 250.

The relay R130, upon operating, prepares, at RA134, a holding circuit for itself and opens, at RA132 and RA135, points in the loop circuit extending to the line switch 50. At RA131, the relay R130 applies ground to the control conductor C156 of the trunk 155, thereby to mark the line 155 as busy in the bank contacts of the connector switches to which it extends and to cause the partial operation of the line switch 50 to disconnect all impedances from across the line conductors of the trunk line. At RA133, the relay R130 prepares a circuit for energizing the slow-to-release relay R140.

Considering now the operation of the timing device 250, when R210 operates, it prepares, at RA211 and RC212, a circuit for energizing the release magnet 254, opens, at RA214, a point in the circuit for energizing the operating magnet 253, and completes, at RA213, a circuit for energizing R220. The last-mentioned circuit extends from ground at RA213 by way of RA244 and the upper winding of R220 to battery. The relay R220, upon operating, applies, at RA221, ground to the output terminal 215 and completes, at RA222 and RC223, an obvious circuit for energizing the pendulum type relay R230. At RA222 and RC224, the relay R230, upon operating, opens a second point in the circuit, traced hereinafter, for energizing the operating magnet 253.

The relay R230, upon operating, completes, at RA231, RC233 and RC234, an obvious circuit for energizing the slow-to-release relay R240. The relay R240, upon operating, prepares, at RA245, an alternative circuit for itself, applies, at RA241 and RC243, multiple ground to the output terminal 215, prepares, at RA246, a point in the circuit for energizing the operating magnet 253, and opens, at RA244, a point in the above-traced operating circuit for R220. At RA241 and RC242,

the relay R240 opens a point in an alternative circuit for energizing R220. The relay R220 now restores to open, at RA222 and RC223, the operating circuit for R230 and further to prepare, at 5 RA222 and RC224, a point in the circuit for energizing the operating magnet 253. When the weighted armature RA231 is released upon the deenergization of R230, it vibrates, pendulum fashion, alternately to engage its two associated contacts RC232 and RC233. Each time one of 10 these contacts is engaged by RA231, a circuit extending by way of RA245 is momentarily completed for energizing R240. Thus, the slow-to-release relay R240 is held operated until the 15 amplitude of vibration of RA231 has been sufficiently reduced to prevent this armature from making contact with its two associated contacts RC232 and RC233. When this occurs, R240 restores to open, at RA246, a point in the circuit 20 for energizing the magnet 253. By proper adjustment of the weighted armature RA231, the time interval during which R240 is held operated may be fixed at any desired value. Preferably, this interval is made sufficient to insure that the 25 ringing operation at the substation A will be completed before R240 restores. When the ringing operation is concluded R120 restores to open, at RA122, the operating circuit for R210. The relay R210, upon restoring, opens at RA213, a 30 point in the above-traced operating circuit for R220 and completes, at RA214, the above-mentioned circuit for energizing the operating magnet 253. Specifically, the last-mentioned circuit extends from ground at RA222 by way of RC224, 35 RA246, RA214 and the winding of the magnet 253 to battery. Upon being energized over this circuit, the magnet 253 attracts its armature, not shown, preparatory to stepping the wiper 252 one step off normal or into engagement with its associated first contact. The actual wiper stepping 40 operation occurs when the relay R240 subsequently restores to open the operating circuit for the magnet 253. When this occurs, the off-normal springs 255 are closed to prepare a point 45 in the circuit for energizing the release magnet 254. At this time, however, R210 is restored so that the operating circuit for the release magnet is open at RA211. With R240 restored and the 50 switch 253 operated to its first off-normal position, the above-noted alternative circuit for energizing R220 is completed, this circuit extending from ground at the first contact of the set 251 by way of the wiper 252, RA241, RC242 and through the lower winding of R220 to battery. 55 The relay R220 now operates to again complete, at RA222 and RC223, the operating circuit for R230, causing the latter relay to attract its weighted armature RA231 to recomplete the operating circuit for R240.

60 From this point on, the operation of the apparatus is quite similar to that described above, it being in fact a repetition. Thus, when R240 operates, it opens, at RA244, the alternative operating circuit for R220, causing this relay to restore to again complete the operating circuit for the magnet 253 and to open the operating circuit for R230. When R240 again restores, after an interval, it recompletes the operating circuit for R220 and opens the operating circuit for the magnet 253. Each time the magnet 253 is energized and deenergized, it steps the wiper 252 one step. 65 Since the first seven contacts of the set 251 are multiplied together and connected to ground, the timing device 200 continues to operate until the 70 wiper 252 is stepped to its eighth off-normal position.

tion. When this occurs, ground is removed at the wiper 252 and its associated eighth contact from the output terminal 215, and a point is opened in the alternative operating circuit for R220. Hence, when R240 restores following the ninth step of 5 the wiper 252, no circuit is available for energizing R220 and the cyclic operation of the apparatus is discontinued. The timing device 200 remains in this condition until R210 is again energized in connection with another call. 10

Since the timing device 200 is commonly associated with all of the rural lines and their terminating repeaters and is provided for the purpose of maintaining each of these repeaters guarded against incoming calls during the use 15 thereof in reverting call connections, it will be apparent that it is desirable for this apparatus to provide at least a minimum guard interval for each of successively initiated reverting calls on different lines. To this end, the device 200 is 20 arranged to be restarted following the initiation of its operation in response to one reverting call and when a second reverting call on a different rural subscriber's line is initiated. In explanation of this mode of operation it will be assumed that, 25 at the time the wiper 252 reaches its seventh off-normal position in connection with the reverting call initiated at the substation A, a second reverting call is initiated on a different rural subscriber's line. When the alternating current relay 30 corresponding to R120 and embodied in the repeater terminating this different subscriber's line operates, it functions to apply ground to C170, thereby to cause the operation of R210. When R210 operates and with the wiper 252 in 35 its seventh off-normal position, a circuit is completed for energizing the release magnet 254, this circuit extending from ground at RC212 by way of RA211, the closed off-normal springs 255 and the winding of the magnet 254 to battery. The 40 release magnet, upon operating, causes the wiper 252 to be returned to its home position in the usual manner. Thus, the timing device 200 is in effect restarted. If this device is allowed fully to 45 complete its operation in connection with a single reverting call, it will not be returned to normal until a second reverting call is initiated, thereby to cause the reoperation of the start relay R210.

Continuing now with the operation of the apparatus provided in the repeater for guarding the 50 line 86 against seizure by one of the connector switches having access thereto, when ground is applied to the output terminal 215 through the operation of R220, a holding circuit for R130 is 55 completed, this circuit extending from ground on the terminal noted by way of C171, RC143, RA142, RA134, and the winding of R130 to battery. With R130 operated, ground is maintained on the control conductor C156 to prevent the repeater or, more particularly, the line 86 from being seized 60 by any one of the connector switches at which the trunk line 155 terminates. Following the ringing operation at the substation A the desired talking connection is completed when the calling and called parties remove their receivers from the respective supporting hooks. When, for example, the receiver 74 is removed from its hook to actuate the hook switch 80 to its off-normal position, the above-traced circuit for energizing the line relay R150 is completed. A similar or parallel circuit for energizing R150 is completed 65 when the called party answers the call. This relay, upon operating, completes, at RA154, a circuit extending by way of RA133 for energizing the slow-to-release relay R140. At RA151 and RC152, 70

75

the relay R150 opens a point in the operating circuit for R110. Obviously, the relay R150 is held operated so long as the receiver 14 is removed from its hook and so long as the receiver at the substation D is not replaced on its hook.

When R140 operates, it completes, at RA141, a holding circuit for R130 independently of the timing device 200, this circuit extending from ground at RA154 by way of RA141, RA142, RA134 and the winding of R130 to battery. The three relays R130, R140 and R150 are thus held operated until such time as the connection is cleared out at the two substations A and D.

When the receivers at the respective substations A and D are restored to their respective hooks, the circuit over which the line relay R150 is held energized is interrupted, causing this relay to restore and open, at RA154, the holding circuits over which R130 and R140 are held energized. The relay R130 now restores to open, at RA134, a further point in its holding circuit and, at RA133, a further point in the operating circuit for R140. When R140 restores, the apparatus is entirely released and is in readiness for further use. It is noted that R140, due to its slow-to-release characteristic, only restores following the restoration of R130. Hence, there is no possibility of R130 being maintained energized even though the timing device 200 is operating at the time the connection is cleared out.

As pointed out in a preceding portion of the specification, there is provided in association with the rural lines a test connector switch 60 which may be used in routing calls from an operator's substation in the automatic exchange to the lines for the purpose of testing the lines to locate defective apparatus and defective lines. The method by which a call is routed from the operator's telephone by way of the test connector switch 40 to a desired one of the rural subscribers' lines is substantially identical to that described above with reference to the operation of the apparatus to establish a connection between the substations B and C. The method by which this test connector switch is prevented from seizing a selected rural line which is busy is, however, considerably different from the method employed for busying the lines in the regular connector switches. More particularly, the relay R100 is provided for preventing the test connector switch from seizing the line 86 when this line is in a busy condition. Relays corresponding to R100 are provided in association with each of the other rural subscribers' lines. When the line 86 is busy in connection with any one of the three types of calls described previously, ground is present on the control conductor C156, this ground being impressed on the conductor noted by R130 when the line is busied during a reverting call, being derived from the line switch 50 when the line is busy in connection with a call to one of the other subscriber's lines, and being derived from one of the connector switches, such, for example, as the switch 40, when the line is busy in connection with a call from one of the other subscriber's lines to a substation on the line 86. Ground as impressed on C156 is extended by way of RA101 and RC102 to the upper terminal of the winding of R100. As a result, if the test connector switch 60 attempts to secure a connection to the line 86, this line will test busy by virtue of the presence of ground on the test conductor C156, this ground being extended through the winding of R100 to the conductor noted. Moreover, no circuit will be completed for energizing

R100 since ground potential is also extended to C106 when the line 86 is selected by the switch 60. Hence, the established talking connection is not interfered with. If, on the other hand, the line 86 is idle at the time the test connector switch 5 attempts to seize the line, battery potential is present on C156, which potential is extended by way of the resistor 106, the winding of R100 and C106 to the test contact of the contact set embodied in the switch 60 which corresponds to the line 86. Since ground is impressed on C106 by the switch 60 when the line 86 is selected, R100 is caused to operate. This relay, upon operating, applies, at RA101 and RC103, ground to the control conductor C106, thereby to mark the line 86 as busy in the various regular connector switches to which the trunk 155 extends. At RA104 and RA105, the relay R100 opens two points in the operating circuit for the alternating current relay R120, thereby to prevent this relay from being energized when ringing current is thereafter conducted by way of the connector switch 60 to the line 86. During the release of a connection routed by way of the test connector switch 60 to the line 86, the relay R100 is caused to restore when ground is removed from C106. Otherwise, the release of such a connection is accomplished in substantially the manner outlined above with reference to the connection established between the substations B and C.

While there has been described what is at present considered to be the preferred embodiment of the invention, it will be understood that various modifications may be made therein, and it is contemplated to cover in the appended claims all such modifications as fall within the true spirit and scope of the invention.

We claim:

1. In a telephone system, an exchange, a non-numerical switch and a plurality of numerical switches located in said exchange, a repeater, a trunk line terminating at one of said numerical switches and at said non-numerical switch, said trunk line extending to said repeater, a subscriber's line extending to said repeater, a plurality of substations associated with said line, means comprising alternating current generators individually provided at said substations for signaling between said stations on reverting calls, means responsive to the operation of any one of said generators for opening a point in said trunk line, thereby to prevent said non-numerical switch from being seized, means also responsive to the operation of any one of said generators for marking said trunk line as busy, thereby to prevent said subscriber's line from being seized by said numerical switch, a relay in said repeater and operative to complete a loop circuit to said non-numerical switch thereby to cause said non-numerical switch to extend the loop circuit to one of said numerical switches, an operating circuit for said relay, and means individually provided at certain of said substations for completing said operating circuit.

2. In a telephone system, an exchange, a non-numerical switch and a plurality of numerical switches located in said exchange, a repeater, a trunk line terminating at one of said numerical switches and at said non-numerical switch, said trunk line also terminating at said repeater and comprising a normally incomplete loop circuit extending to said non-numerical switch, a subscriber's line extending to said repeater, a plurality of substations associated with said subscriber's line, a relay operative to complete said

loop circuit, thereby to cause said non-numerical switch to extend said loop circuit to one of said numerical switches, an operating circuit for said relay, means individually provided at certain of said substations for completing said operating circuit, means comprising alternating current generators individually provided at said substations for signaling between said substations on reverting calls, means responsive to the operation of any one of said generators for marking said trunk line as busy, thereby to prevent said subscriber's line from being seized by said one of said numerical switches, and means also responsive to the operation of any one of said generators for opening a point in said loop circuit, thereby to maintain said loop circuit open independently of said relay.

3. In a telephone system, an exchange, a non-numerical switch and a plurality of numerical switches located in said exchange, a repeater, a trunk line terminating at one of said numerical switches and at said non-numerical switch, said trunk line also terminating at said repeater and comprising a normally incomplete loop circuit extending to said non-numerical switch, a subscriber's line extending to said repeater, a plurality of substations associated with said subscriber's line, an impulsive device at one of said substations, a pulsing relay operative to complete said loop circuit, thereby to cause said non-numerical switch to condition one of said numerical switches to respond to the operation of said pulsing relay, an operating circuit for said relay, said operating circuit being arranged to be controlled by said impulsive device, means at said one substation for completing said operating circuit, means comprising alternating current generators individually provided at said substations for signaling between said substations on reverting calls, means responsive to the operation of any one of said generators for marking said trunk line as busy, thereby to prevent said subscriber's line from being seized by one of said numerical switches, and means also responsive to the operation of any one of said generators for opening a point in said loop circuit, thereby to maintain said loop circuit open independently of said relay.

4. In a telephone system, an exchange, a non-numerical switch and a plurality of numerical switches located in said exchange, a repeater, a trunk line terminating at one of said numerical switches and at said non-numerical switch, said trunk line also terminating at said repeater and comprising a normally incomplete loop circuit extending to said non-numerical switch, a subscriber's line extending to said repeater, a plurality of substations associated with said subscriber's line, an impulsive device provided at one of said substations, a pulsing relay operative to complete said loop circuit, thereby to cause said non-numerical switch to condition one of said numerical switches to respond to the operation of said pulsing relay, an operating circuit for said relay, said operating circuit being arranged to be controlled by said impulsive device, means at said one substation for completing said operating circuit, means comprising alternating current generators individually provided at said substations for signaling between said substations on reverting calls, an alternating current relay including a pair of windings connected and arranged to be differentially energized in response to the completion of said operating circuit, said windings being cumulatively energized to cause the operation of said alternating current relay

in response to the operation of any one of said generators, means responsive to the operation of said alternating current relay for marking said trunk line as busy thereby to prevent said subscriber's line from being seized by one of said numerical switches, and means also responsive to the operation of said alternating current relay for opening a point in said loop circuit, thereby to hold said loop circuit open independently of said first-named relay.

5. In a telephone system, an exchange, a non-numerical switch and a plurality of numerical switches located in said exchange, a repeater, a trunk line terminating at one of said numerical switches and at said non-numerical switch, said trunk line also terminating at said repeater and comprising a normally incomplete loop circuit extending to said non-numerical switch, a subscriber's line extending to said repeater, a plurality of substations associated with said subscriber's line, a relay operative to complete said loop circuit, thereby to cause said non-numerical switch to extend said loop circuit to one of said numerical switches, an operating circuit for said relay, means individually provided at certain of said substations for completing said operating circuit, means comprising alternating current generators individually provided at said substations for signaling between said substations on reverting calls, an alternating current relay connected and arranged to operate only in response to the operation of any one of said generators, means responsive to the operation of said alternating current relay for opening a point in said loop circuit, thereby to hold said loop circuit open independently of said first-named relay.

6. In a telephone system, an exchange, a non-numerical switch and a plurality of numerical switches located in said exchange, a repeater, a trunk line terminating at one of said numerical switches and at said non-numerical switch, said trunk line also terminating at said repeater and comprising a normally incomplete loop circuit extending to said non-numerical switch, a subscriber's line extending to said repeater, a plurality of substations associated with said subscriber's line, a relay operative to complete said loop circuit, thereby to cause said non-numerical switch to extend said loop circuit to one of said numerical switches, an operating circuit for said relay, means individually provided at certain of said substations for completing said operating circuit, means comprising alternating current generators individually provided at said substations for signaling between said substations on reverting calls, an alternating current relay connected and arranged to operate only in response to the operation of any one of said generators, a relay operative to mark said trunk line as busy, thereby to prevent said subscriber's line from being seized by one of said numerical switches, said last-named relay also being operative to open a point in said loop circuit, an operating circuit for said last-named relay, said last-named operating circuit being arranged to be completed each time said alternating current relay operates, a holding circuit for said last-named relay, and means operative in response to the operation of said alternating current relay for completing said holding circuit.

7. In a telephone system, an exchange, a non-numerical switch and a plurality of numerical switches located in said exchange, a repeater, a trunk line terminating at one of said numerical switches and at said non-numerical switch, said trunk line also terminating at said repeater and comprising a normally incomplete loop circuit extending to said non-numerical switch, a subscriber's line extending to said repeater, a plurality of substations associated with said subscriber's line, a relay operative to complete said loop circuit, thereby to cause said non-numerical switch to extend said loop circuit to one of said numerical switches, an operating circuit for said relay, means individually provided at certain of said substations for completing said operating circuit, means comprising alternating current generators individually provided at said substations for signaling between said substations on reverting calls, an alternating current relay connected and arranged to operate only in response to the operation of any one of said generators, a relay operative to mark said trunk line as busy, thereby to prevent said subscriber's line from being seized by one of said numerical switches, said last-named relay also being operative to open a point in said loop circuit, an operating circuit for said last-named relay, said last-named operating circuit being arranged to be completed each time said alternating current relay operates, a holding circuit for said last-named relay, a timing device operative in response to the operation of said alternating current relay for completing said holding circuit and for maintaining said holding circuit completed for a predetermined time interval, and means for maintaining said holding circuit completed independently of said timing device.

8. In a telephone system, an exchange, a non-numerical switch and a plurality of numerical switches located in said exchange, a repeater, a trunk line terminating at one of said numerical switches and at said non-numerical switch, said trunk line also terminating at said repeater and comprising a normally incomplete loop circuit extending to said non-numerical switch, a subscriber's line extending to said repeater, a plurality of substations associated with said subscriber's line, an impulsive device provided at one of said substations, a pulsing relay operative to complete said loop circuit, thereby to cause said non-numerical switch to condition one of said numerical switches to respond to the operation of said pulsing relay, an operating circuit for said relay, said operating circuit being arranged to be controlled by said impulsive device, means at said one substation for completing said operating circuit, means comprising alternating current generators individually provided at said substations for signaling between said substations on reverting calls, an alternating current relay connected and arranged to operate only in response to the operation of any one of said generators, a relay operative to mark said trunk line as busy, thereby to prevent said subscriber's line from being seized by one of said numerical switches, said last-named relay also being operative to open a point in said loop circuit, an operating circuit for said last-named relay, said last-named operating circuit being arranged to be completed each time said alternating current relay operates, a holding circuit for said last-named relay, a timing device operative in response to the operation of said alternating current relay for completing said holding circuit and for maintaining said holding cir-

cuit completed for a predetermined time interval, and means for maintaining said holding circuit completed independently of said timing device.

9. In a telephone system, a subscriber's line, a connector switch having access to said line, a plurality of substations associated with said line and individually including telephones, means comprising alternating current generators individually provided at said substations for signaling between said substations, means operative in response to the operation of any one of said generators for marking said line as busy, thereby to prevent said line from being seized by said connector switch, a timing device for maintaining said last-named means operated independently of said generators, means responsive to the operation of any one of said generators for initiating the operation of said timing device, and means operative in response to the connection of any one of said telephones to said line for maintaining said second-named means operated independently of said timing device, said last-named means only being operative following the operation of one of said generators.

10. In a telephone system, a subscriber's line, a connector switch having access to said line, a plurality of substations associated with said line and individually including telephones, means comprising alternating current generators individually provided at said substations for signaling between said substations, a relay operative to mark said line as busy, thereby to prevent said line from being seized by said connector switch, an operating circuit for said relay, a holding circuit for said relay, means operative in response to the operation of any one of said generators for completing said operating circuit, a timing device for completing said holding circuit and for maintaining said holding circuit completed for a predetermined time interval only, means responsive to the operation of any one of said generators for initiating the operation of said timing device, and means operative in response to the connection of any one of said telephones to said line for maintaining said holding circuit completed independently of said timing device, said last-named means only being operative to maintain said holding circuit completed if said relay is operated at the time said one telephone is connected to said line.

11. In a telephone system, a subscriber's line, a connector switch having access to said line, a plurality of substations associated with said line and individually including telephones, means comprising alternating current generators individually provided at said substations for signaling between said substations, a relay operative to mark said line as busy, thereby to prevent said line from being seized by said connector switch, an operating circuit for said relay, a holding circuit for said relay, said holding circuit including two branches, means operative in response to the operation of any one of said generators for completing said operating circuit, a timing device for completing one branch of said holding circuit and for maintaining said holding circuit completed for a predetermined time interval only, means responsive to the operation of any one of said generators for initiating the operation of said timing device, a second relay operative to complete the other branch of said holding circuit, an operating circuit for said second relay, said last-named operating circuit being prepared upon the operation of said first-named relay, and a third relay operative in response to the connection of any one of said telephones to said line for complet-

- ing said last-named operating circuit and for preparing said other branch of said holding circuit.
12. In a telephone system, a plurality of subscribers' lines, an automatic switch having access to said lines, a plurality of substations associated with each of said lines, magneto generators individually provided at said substations, a cyclically operating timing device, means individually associated with said lines and each including said timing device for marking the individual ones of said lines as busy, thereby to prevent said lines from being seized by said automatic switch, and control means for said timing device, said timing device and the control means therefor being so connected and arranged that said timing device is started in operation in response to the operation of any one of said generators and the operating cycle thereof is interrupted and a new cycle started in response to the operation of a second of said generators and in the event the first operating cycle is not completed before the operation of said second generator is started.
13. In a telephone system, a plurality of subscribers' lines, an automatic switch having access to said lines, a plurality of substations associated with each of said lines, magneto generators individually provided at said substations, a timing device including a stepping switch having a home position, a start relay operative to initiate the operation of said timing device, said timing device being operative through a predetermined cycle each time the operation thereof is initiated with said switch in said home position, means individually associated with said lines and each including said timing device for marking the individual ones of said lines as busy, thereby to prevent said lines from being seized by said automatic switch, means responsive to the successive operation of said generators or to the repeated operation of one of said generators for repeatedly energizing said start relay, and means for returning said switch to its home position each time said start relay is energized after said timing device has started an operating cycle.
14. In a telephone system, a plurality of subscribers' lines, an automatic switch having access to said lines, a plurality of substations associated with each of said lines, magneto generators individually provided at said substations, a timing device commonly associated with said lines and operative through a predetermined cycle each time its operation is initiated, means responsive to the operation of a generator provided at a substation associated with one of said lines for initiating the operation of said timing device, means including said timing device for marking said one line as busy, thereby to prevent said one line from being seized by said automatic switch, means responsive to the operation of a generator provided at a station associated with a second of said lines for starting said timing device on a new cycle of operation, and means including said timing device for marking said second line as busy, thereby to prevent said second line from being seized by said connector switch.
15. Timing apparatus comprising, in combination, a switch having a home position and operative to a predetermined off-normal position, an output terminal, a start relay, means responsive to the operation of said start relay for initiating the operation of said switch, means controlled by
- said start relay for applying a predetermined potential to said output terminal, means controlled by said switch for maintaining said predetermined potential on said output terminal independently of said start relay, and means responsive to the operation of said switch to said predetermined off-normal position for removing said predetermined potential from said output terminal.
16. Timing apparatus comprising, in combination, a switch having a home position and operative to a predetermined off-normal position, an output terminal, a start relay, means responsive to the operation of said start relay for initiating the operation of said switch, means controlled by said start relay for applying a predetermined potential to said output terminal, means controlled by said switch for maintaining said predetermined potential on said output terminal independently of said start relay, and means responsive to a second operation of said start relay for returning said switch to said normal position.
17. Timing apparatus comprising, in combination, a switch having a home position and operative to a predetermined off-normal position, an output terminal, a start relay, means responsive to the operation of said start relay for initiating the operation of said switch, means controlled by said start relay for applying a predetermined potential to said output terminal, means controlled by said switch for maintaining said predetermined potential on said output terminal independently of said start relay, means responsive to a second operation of said start relay for returning said switch to said normal position, and means responsive to the operation of said switch to said predetermined off-normal position for removing said predetermined potential from said output terminal and for arresting the operation of said switch.
18. In a telephone system, a line, a pair of automatic switches each operative to extend a telephone connection to said line, said line normally being connected to be accessible only to one of said switches, a relay arranged to be controlled by the other of said switches, said relay being operative to rearrange the connections so that said line is accessible to said other switch, and means operative when said line is made busy in a connection not routed by way of said other switch for rendering said other switch ineffective to control said relay.
19. In a telephone system, a line, a pair of automatic switches each operative to extend a telephone connection to said line, each of said switches having a predetermined operating position corresponding to said line, said line normally being connected to be accessible only to one of said switches, a relay connected and arranged normally to operate in response to the operation of the other of said switches to its said predetermined operating position, said relay being operative to rearrange the circuit connections so that said line is accessible to said other switch, and means operative when said line is made busy in a connection not routed by way of said other switch for rendering said relay inoperative in response to the operation of said other switch to its said predetermined position.
